United States Patent Office

Des. 228,516

Patented Oct. 2, 1973

228,516

PENDANT OR THE LIKE

Wesley Michael Brooks, 4615 Holland-Sylvania Road,
Apt. 38, Toledo, Ohio 43623; Clifford E. Forman,
Rte. 2, Box 260, Delta, Ohio 43515; and Roger T.
Markey, Rte. 1, Box 91B, Swanton, Ohio 43558

Filed Dec. 23, 1971, Ser. No. 211,849

Term of patent 14 years

Int. Cl. D11—01

U.S. Cl. D45—16 A

FIG. 1

FIG. 3

FIG. 1 is a top plan view of a pendant showing our new design;

FIG. 2 is a bottom edge view; and

FIG. 3 is a right side view thereof rotated 90 degrees clockwise.

We claim:

The ornamental design for a pendant or the like, substantially as shown.
